DESIGN FOR A DISPLAY BOX

James P. Sawyer, North Tarrytown, N. Y., assignor to Prince Matchabelli, Inc., New York, N. Y., a corporation of New York

Application December 18, 1944, Serial No. 116,979

Term of patent 14 years

(Cl. D80—5)

To all whom it may concern:

Be it known that I, James P. Sawyer, a citizen of the United States, residing at North Tarrytown, in the county of Westchester and State of New York, have invented a new, original, and ornamental Design for a Display Box, of which the following is a specification, reference being had to the accompanying drawing forming a part thereof.

box embodying my new design shown in closed position; and

The two panel strips shown on the top and front of the box in Figure 1 continue around the box.

I claim:

The ornamental design for a display box, as shown and described.

JAMES P. SAWYER.
